REFRIGERATING APPARATUS

Harry B. Hull, Dayton, Ohio, assignor, by mesne assignments, to General Motors Corporation, a corporation of Delaware

Application August 28, 1930, Serial No. 478,486
Renewed October 10, 1932

5 Claims. (Cl. 62—116)

This invention relates to refrigerating apparatus and more particularly to a cabinet for use with refrigerating apparatus.

One of the objects of this invention is to provide an improved cabinet in which the refrigerating unit is readily accessible for repairs either while in the cabinet or which may be readily removed from the cabinet for repairs.

According to this invention a cabinet is provided which presents a symmetrical appearance both from the front and from the side and at the same time permits ready access to the machinery while it is in place in the cabinet and also permits the ready removal of the entire refrigerating system from the cabinet without undue dismantling of the cabinet or the necessity of lifting the system to an undue height. This is accomplished by providing integral outer side panels for the cabinet which extends above the platform on which the refrigerating system is supported to thus provide a machinery compartment in cooperation with a removable front upper panel and top.

Further objects and advantages of the present invention will be apparent from the following description, reference being had to the accompanying drawings, wherein a preferred form of the invention is clearly shown.

In the drawings:

30 Fig. 1 is a perspective view of a cabinet embodying features of the invention.

Fig. 2 is a vertical view in cross section of the cabinet shown in Fig. 1 and showing the refrigerating unit installed in the cabinet, the view being taken on the line 2—2 of Fig. 1.

Fig. 3 is a fragmentary view in cross section of a portion of the cabinet shown in Figs. 1 and 2.

Fig. 4 is a perspective view of a cabinet embodying features of the invention.

40 Fig. 5 is a vertical view in cross section of a modified form of refrigerating apparatus embodying features of the invention.

Fig. 6 is a perspective view in elevation of a portion of the cabinet shown in Fig. 5; and

45 Fig. 7 is a view in perspective of a modified form of cabinet.

Referring to the drawings and particularly to Figs. 1 and 2 there is shown a cabinet 20 of box-like structure comprising a food compartment 21 formed by side walls 22 and 23, bottom wall 24 and a partition wall 25. The partition wall forms the top wall of the food compartment and divides the cabinet into a plurality of compartments, namely, the food compartment 21 and a machinery compartment 28. The side walls of the

cabinet 20 include an outer metal casing 30, insulation 32 interposed between the outer casing and an inner lining 34. The food compartment is provided with an opening 35 closed by door 36.

The opposed side walls 32 are provided with integral extensions formed by the outer metal casing 30. These integral extensions extend above the wall 35 and form side walls for the machinery compartment 28 as shown at 40 and 41. By this arrangement there is provided above the 10 partition wall an opening 42 at the front of the cabinet, an opening 43 at the top of the cabinet, and an opening 44 at the rear of the cabinet. As shown in Fig. 3 the machinery compartment 28 is provided with upright posts 50 provided with 15 threaded plugs 51 in the posts at the front of the cabinet. These posts at the front of the cabinet provide means for securing a removable closure means or panel 55 to the cabinet 20 by screws 56 inserted into the plugs 51. 20

The removable closure means 55 is arranged for closing the opening 42 at the front of the cabinet. A movable cover or closure means 59 is provided for closing the opening 43 at the top of the cabinet while the opening 44 at the rear of 25 the cabinet remains open in order to permit the circulation of air into and out of the machinery compartment.

The food compartment 21 is adapted to be cooled by a cooling element or evaporator 60 depending from the wall 25. Preferably the evaporator is constructed of sheet metal having duct means 61 for the circulation of the refrigerant and is adapted to enclose a plurality of ice making receptacles 64. The evaporator 60 is supplied with liquid refrigerant by a refrigerant liquefying element 70 under the control of an expansion valve 71. The liquefying element is mounted on the partition wall 25 and includes preferably a motor driven compressor 72, condenser 74 and a motor driven fan 76 connected in parallel with the motor driven compressor for cooling the condenser. The compressor withdraws gaseous refrigerant from the evaporator 60 through a flexible vapor conduit 77, compresses 35 the gaseous refrigerant and delivers it to the condenser 74 wherein it is liquefied and from which it is delivered to a flexible supply conduit 80 connected to the expansion valve 71. Preferably the pipe 77 extends through a recessed portion 81 in 50 the partition wall 25. A thermostat 82 is connected to the rear of the evaporator 60 and is operatively connected with a switch 84 for starting and stopping the motor driven compressor in response to the temperature of the evaporator 60 55

and compartment 21. Preferably the motor driven compressor includes a motor and compressor unit hermetically sealed in the compressor casing. The switch 84 is also adapted to control the operation of the motor driven fan. Thus the fan operates during the operation of the motor driven compressor.

In the chosen illustration the refrigerant liquefying element 70 is mounted on an angle iron frame 90 which extends into the food compartment 21 and to which the evaporator 60 is secured by bolts 92.

Preferably the refrigerating unit which includes the liquefying element and the cooling element may be removed as a unit from the cabinet 20. This may be accomplished by removing the closure means 55 and by moving the liquefying element through the opening 42 at the front of the cabinet, which opening is large enough to permit the insertion and removal of the liquefying element therethrough. The pipes 77 and 80 can be removed from the cabinet 20 by removing a front panel 94 which may be removably secured to the cabinet in any suitable manner. Thus the entire refrigerating unit can be removed as a unit without disconnecting the pipes 77 and 80 by simply removing the closure means 55 then removing the liquefying element through the opening 42 at the front of the cabinet, and then by removing the panel 94 the pipes 77 and 80 can be removed along with the liquefying element and evaporator which is removed through the door opening when the bolts 92 are removed. This arrangement is particularly advantageous in event it is desired to remove the refrigerant unit to make repairs, in that, it is unnecessary to move the cabinet. Also an inspection of the refrigerating unit can be made at all times without moving the cabinet.

Referring to Figs. 5 and 6 there is shown a modified form of refrigerating apparatus comprising a cabinet designated generally by the numeral 100. The cabinet 100 comprises insulated side walls 102 and 103, a movable top partition wall 104 and bottom wall 105 which form a food compartment 108. The side walls 102 and 103 are formed by an outer metal casing 109, insulation 110 interposed between said casing and an inner metal lining 112. The top wall comprises a frame 118 provided with an opening 119 sealed by the movable partition wall 104 which is provided with an insulating gasket seal 120 adapted to rest on a recessed portion 121 of the frame 118. The partition wall 104 is adapted to carry a refrigerating unit comprising in general a cooling element 130 depending from said wall and refrigerant liquefying element 135 mounted on said wall. The opening 119 in the frame 118 is of sufficient size so as to permit the insertion and removal of the cooling element 130 therethrough, while the entire refrigerating unit is removable from the cabinet along with the partition wall. The liquefying element 135 includes a compressor 137 which withdraws the gaseous refrigerant from the cooling element 130 through a vapor pipe 140. The compressor compresses the gaseous refrigerant and delivers it to a coiled condenser 141 wherein it is liquefied and from which it is delivered to a receiver 142. The liquefying element 135 delivers the liquid refrigerant from the receiver 142 to the cooling element 130 through a supply conduit 144 under the control of an expansion valve 145 connected therewith. A thermostat 150 is connected to the rear of the cooling element 130 and is operatively connected with

a switch 151 for starting and stopping the motor driven compressor and a fan 153 which is used for cooling the liquid in the condenser 141. The switch 151 is provided with a control 155 which permits an external adjustment of said switch to vary the operating periods of the compressor. The outer metal casing 109 is provided with integral extensions on the side walls 103 which extend upwardly above the partition wall 104 thus providing side walls 158 and 159 which serve to form the side wall of a machinery compartment 160. This arrangement provides an opening 162 at the front of the cabinet and above the movable wall 104, an opening 164 at the top of the cabinet and an opening 166 at the rear of the cabinet. The openings 162 and 164 are adapted to be closed by a removable closure means 170. As shown in Figs. 5 and 6 the side walls 158 and 159 are provided with an arcuate portion 171 conforming substantially to the curvature of the coiled condenser 141 and a relatively low horizontal portion 172 at the front of the cabinet. The closure means 170 is shaped to conform to the shape of the side walls 158 and 159. By the present arrangement inspection of and repairs on the refrigerating unit may be easily made and if desired the entire refrigerating unit may be removed as a unit by simply removing the removable closure means 170 and moving the partition wall 104 upwardly until the lowermost portion of the cooling element 130 is above the frame member 118 and then move the partition wall 104 which carries the refrigerating unit to the front of the cabinet to thus remove said unit from the cabinet.

Fig. 7 is a modification of the cabinet shown in Figs. 5 and 6. As shown the cabinet 200 is provided with integrally formed extensions extending above a top wall 201 of a food compartment 202. In this embodiment of the invention the side walls of the cabinet which extend above the top of the food compartment are on a horizontal plane and the removable closure means 207 is provided with drop sides 209 to cover the space between the top of the walls 210 and the top of said closure means. In all other respects the cabinet 200 is similar to cabinet 100 shown in Figs. 5 and 6.

Referring to the modification shown in Fig. 4, there is shown a cabinet designated 225 constructed substantially like the cabinet shown in Figs. 1 and 2. Thus the cabinet 225 is provided with an inner lining 227 and an outer metal casing 229. Insulation is interposed between the lining 227 and casing 229 which lining, casing and insulation form the side walls of a food compartment 231. In this modification the top wall of the cabinet comprises a frame 235 provided with an opening 236, which opening is of sufficient size to permit the insertion and removal of the cooling element for cooling the compartment 231. The outer metal casing 229 is provided with integral extensions which extend above the frame 235 thus forming side walls 240 and 241 of a machinery compartment. This arrangement provides an opening 242 at the front of the cabinet and opening 244 at the top of the cabinet and an opening 246 at the rear of the cabinet. In this particular embodiment the cabinet 225 is provided with an integrally formed closure means 250 comprising a vertical portion 252 for closing the opening 242 and a horizontal portion 253 for closing the top opening 244. The closure means 250 may be secured to the cabinet in any suitable manner preferably by screws inserted through openings 255 provided in said closure

means. The opening 236 in frame 235 is adapted to be sealed by a removable partition wall of the type shown in Fig. 5 and there designated 104. The partition wall when used in connection with 5 the frame 235 is adapted to carry a cooling element depending from said refrigerating wall and a refrigerant liquefying element mounted on said wall. Preferably a cooling element as shown in Fig. 5 may be used in the cabinet 225. Any suitable liquefying element may be used in the cabinet 225, and for instance, the liquefying element 270 as shown in Figs. 1 and 2 or the liquefying element of the type shown in Fig. 5. This arrangement permits inspection of and repairs to 10 be made on the refrigerating unit from the front of the cabinet and if it is desired to remove said unit from the cabinet all that is necessary is to remove the closure means 250 from the cabinet and then raise the partition wall upwardly until 15 the lowermost portion of the cooling element is above the frame 235 and then move the unit and wall from the cabinet through the opening 242 at the front of the cabinet. Thus the refrigerating unit can be removed from the cabinet without 20 removing said cabinet and this may be accomplished with minimum movement of said unit in view of the opening 242 at the front of said cabinet.

From the foregoing it will be noted that I have 30 provided a refrigerating apparatus comprising a cabinet which houses a refrigerating unit and have arranged said refrigerating unit in a readily accessible manner for inspection thereof or for making repairs thereon either in the cabinet or 35 said unit may be readily removed therefrom for making any repairs without the necessity of moving the cabinet. It will also be noted that the unit is either inserted into the cabinet from the front thereof or inserted into the cabinet with 40 a minimum upward movement of said unit. Furthermore by providing integrally formed side walls on the cabinet the symmetrical appearance of the cabinet is retained.

While the form of embodiment of the invention as herein disclosed constitutes a preferred form, it is to be understood that other forms might be adopted, all coming within the scope of 45 the claims which follow.

What is claimed is as follows:

50 1. Refrigerating apparatus comprising in combination a cabinet provided with side walls forming a food compartment and a door opening in one side wall thereof leading to said compartment, a partition wall forming the top of said food compartment, opposed side walls of said cabinet extending above said wall providing an opening thereabove at the front, rear and top of the cabinet, and removable closure means for

said opening at the front and top of said cabinet.

2. Refrigerating apparatus comprising in combination a cabinet provided with side walls forming a food compartment and a door opening in one side wall thereof leading to said compartment, 5 a partition wall forming the top of said food compartment, opposed side walls of said cabinet extending above said wall providing an opening thereabove at the front and top of said cabinet, and removable closure means for said opening 10 at the front and top of said cabinet.

3. Refrigerating apparatus comprising in combination a cabinet provided with side walls forming a food compartment, the top of said food compartment comprising a frame provided with an 15 opening, a movable wall adapted to seal said opening, a refrigerating unit carried by said movable wall, said unit comprising a cooling element depending from said wall and insertable into and removable from said food compartment through 20 said frame opening, said unit also including a refrigerant liquefying element mounted on said movable wall and a pipe connection interconnecting said elements, opposed sides of said cabinet extending above said frame and providing an 25 opening thereabove at the front, top and rear of said cabinet, removable closure means for the opening at the front and top of said cabinet, said opposed sides and removable closure means enclosing said liquefying element, said opening at 30 the front of the cabinet being of sufficient width to permit the removal of said unit therethrough.

4. A refrigerator cabinet comprising an inner liner forming the sidewalls of a food compartment, insulation surrounding the inner liner, an 35 outer sheet metal casing surrounding the insulation, a plurality of wall portions of the outer casing projecting beyond the other wall portions, movable wall portions cooperating with the extending portions of the outer metal casing to form 40 an enclosure in conjunction with a wall of the food compartment, said movable wall portions forming two complete wall portions of the machinery compartment.

5. A refrigerator cabinet comprising an inner 45 liner forming the sidewalls of a food compartment, insulation surrounding the inner liner, an outer sheet metal casing surrounding the insulation, a plurality of wall portions of the outer casing projecting beyond the other wall portions, 50 movable wall portions cooperating with the extending portions of the outer metal casing to form an enclosure in conjunction with a wall of the food compartment, said movable wall portions being a rigid unitary structure forming two adjacent 55 complete wall portions of the machinery compartment.

HARRY B. HULL.
